BUILDING CONSTRUCTION

Filed March 26, 1926

FIG. 1.

FIG. 2.

FIG. 3.

FIG. 4.

Inventor-
ISAAC T. KAHN,

Attorney.

UNITED STATES PATENT OFFICE

ISAAC T. KAHN, OF CLEVELAND, OHIO

BUILDING CONSTRUCTION

Application filed March 26, 1926. Serial No. 97,579.

My invention relates to improvements in building construction, and more particularly, to the advantageous support of metallic structural members, such as I-beams and the like, from the top flanges thereof; the object of my invention being to afford a cheap and efficient means for erecting structural members of a building.

My invention may be advantageously described in connection with the erection of structures employing so-called metallic lumber, comprising light channeled members which are united back to back by spot welding to approximate the cross section of an I-beam. This metallic lumber affords a convenient and inexpensive medium for building construction when provided with cheap and efficient supporting means. The latter I have accomplished by supporting the metallic lumber from its upper flanges preferably by means of opposing members embracing the web and positioned in vertical planes to extend beneath the terminal upper flange members.

Accordingly, I shall describe my improvement in a building construction embodying such metallic lumber supported by the simplest type of underextending member positioned beneath the upper flanges thereof, although my improvements are not necessarily limited to the particular means set forth for explaining the same, nor as illustratively shown in the accompanying drawing, wherein:

Figure 1 is a view, partly in transverse section, of a girder, carrying the two opposed ends of metallic lumber members from their upper flanges by means of a simple angle-bar bracket construction in accordance with my invention.

Fig. 2 is a fragmentary plan view thereof, partially broken away, and in section.

Fig. 3 is a fragmentary section on line 3-3,

Fig. 1, and

Fig. 4 is a perspective view, terminally sectioned, illustrating a supporting bracket member adapted for the improved building construction herein defined.

Throughout the several figures of the draw-

ing I have employed the same character of reference to indicate similar parts.

The essentials of a building construction sufficient to explain my invention are shown in the aforesaid drawing to typify the same and comprise a heavy I-beam or girder *a*, which may be assumed to be terminally supported by the building walls in the usual manner. Laterally thereof there are shown the broken away ends *b* of two lengths of metallic lumber comprising channel-members *b*' *b*' united along their webbed faces by spot welding, for example. Thus they constitute a fabricated I-beam.

Fig. 4 illustrates a preferred composite member for terminally supporting the metallic lumber *b*, *b*', or other flanged or I-beam structures from the top flanges thereof. This comprises the angle bars *c*, *c*, united by the bolts *d*, *d*, and having the lugs *c*' *c*' stamped from their base portions to form attaching clips, as best shown in Fig. 1. This supporting member may be of any suitable length for extending beneath the upper flanges of the joist members in order terminally to carry the superimposed weight.

The angle bars may be tightened against the embraced webs by means of the bolts and nuts *d*, *d*' advantageously, but the joist members primarily are supported by the vertically positioned embracing lengths of the angle bars *c*, *c*'. Thus, these I-beam sections require no reinforcement and no preparation by way of trimming or punching bolt holes, for example, hence the building construction described is extremely easy to erect and is cheap and serviceable for the relatively lighter loadings.

I am aware that I-beams previously have been erected by means of terminally embracing members clamped to the webs thereof by means of bolts passing through and through the respective thicknesses of metal and forming bracketed supports upon metallic posts and the like. This construction, however, is dissimilar to the embodiment of my invention in that the structurally unattached but terminally supported I-beams are carried from their top flanges and the supporting member bears directly upon the upper face of

the joist, thereby obviating the expense for any labor in preparing and adapting the members for erection as a building unit.

Having now described the preferred embodiment of my invention, I claim as new and desire to secure by Letters Patent, the following:

1. In a building construction, the combination with a supporting member comprising horizontally spaced vertically positioned metallic bars and means for limiting their spaced relation, of an unattached flanged supported member terminally inserted therebetween and carried by upper suspending flanges upon the vertical bars, substantially as set forth.
2. In a building construction, the combination with a supporting member comprising horizontally spaced parallel bars in vertical position, and means for maintaining them in their approximate relation, of unattached flanged supported members inserted with their flanges bearing terminally upon the upper edges of said bars and their webs embraced therebetween, substantially as set forth.
3. In a building construction, the combination with a girder, of a supporting member carried thereon, comprising horizontally spaced parallel vertical bars and means for limiting them in spaced relation, and unattached I-beam members inserted between the opposite ends of said supporting member with their upper flanges bearing upon the vertical bars and with their webs embraced therebetween, substantially as set forth.
4. In a building construction, the combination with a girder, of a supporting member carried thereon, comprising angle bars and bolts extending through the opposed vertical members thereof, and means for attaching the same to the girder, and lengths of unattached metallic lumber terminally and oppositely supported between the opposing bars by their upper flanges with their webs inserted for a distance therebetween, substantially as set forth.
5. In a building construction, the combination with a supporting girder, of a supporting member carried thereon and extending transversely at a distance from either side thereof, comprising closely spaced parallel members, of unattached flanged supported members terminally inserted between said spaced members and carried thereon by their upper flanges, substantially as set forth.
6. In a building construction, the combination with a composite supporting member having extended horizontally spaced parallel bars forming terminal supports, of means for intermediately mounting said member, and unattached opposing flanged metallic lumber units terminally entered between said parallel bars and carried thereon by their superposed flanges, substantially as set forth.
7. In a building construction, the combina-

tion with a composite supporting member having terminally extended spaced parallel bar supports, of means intermediately mounting said member in the building construction, and unattached opposing flanged metallic lumber units terminally entered between said parallel bars and carried thereon by their upper flanges, and means for clamping the webs of said units between the spaced terminal bars, substantially as set forth.

8. The herein described metal joist supporter comprising a pair of angle bar sections secured to the end of the joist, close against the web and close under the top flange thereof and extending longitudinally beyond the joist end, and adapted to be secured to, and rest upon the top flange of a transverse I-beam.

9. In a metal I-beam structure, a joist hanger joint comprising a supporting beam, a pair of beams arranged oppositely and transverse of the supporting beam, the ends of said beams being supported by means of a pair of angle bar sections extending over the top of the supporting beam, and secured to the ends of the opposing beams under the top flanges and close against the webs of each.

10. A new article of manufacture, a metal I-beam joist supporter, comprising angle bar sections, said sections being clamped to the angular surface under the top flange on either side of the web of a joist end and extending over the top surface of the supporting beam.

In testimony whereof I do now affix my signature.
